HOOP WHIRLER

Paul Masse, Montreal, Quebec, Canada, assignor to
Palma Adrien Lefebvre, Cornwall, Ontario, Canada

Filed Jan. 12, 1959, Ser. No. 54,135

Term of patent 7 years

(Cl. D34—5)

The broken line showing of a hoop is for illustrative purposes only.

I claim:

The ornamental design for a hoop whirler, as shown and described.
